UNITED STATES PATENT OFFICE.

PERCY NORMAN WILLIAMS, OF PELHAM MANOR, NEW YORK.

REGULATING DEVICE FOR ORTHODONTIC CORRECTING APPLIANCES.

Application filed June 25, 1925. Serial No. 39,628.

To all whom it may concern:

Be it known that I, PERCY NORMAN WILLIAMS, a citizen of the United States, and resident of Pelham Manor, in the county of Westchester and State of New York, have invented certain new and useful Improvements in Regulating Devices for Orthodontic Correcting Appliances, of which the following is a specification.

10 This invention relates to improvements in the art and practice of orthodontia and more particularly to a device for regulating the tensional adjustment of orthodontic correcting appliances.

15 A principal object of my invention is the provision of a regulating device that will enable the tension of a correcting appliance to be controlled by a micrometric adjustment, to a predetermined and measurable value. Another principal object of my invention is to provide a device of the character described, that will permit the tensioning adjustment of the correcting appliance to be performed while the appliance 20 is disposed in position on its plaster-cast model. A further feature of this invention is the provision of an actuating means that will facilitate the adjustment of tension of the correcting appliance, permitting the regulation of the adjustment to be carried out to as fine a degree as desired.

25 The attainment of the foregoing and further advantages will become evident from the description following and in the accompanying drawing, wherein I have set forth and illustrated a practical embodiment of my invention.

30 In the drawing similar reference characters indicate the similar parts in the various views.

Figure 1 shows the complete assembly of the correcting appliance and plaster-cast model mounted on the device, in perspective.

35 Fig. 2 shows a view in section through the center of the device, laterally.

Fig. 3 shows an elevation of the movable base-plate member of the device.

40 Fig. 4 is a sectional view showing the guide pin means for aligning the base-plate members of the device.

45 The device embodied in my invention is composed of the two substantially similar base-plate members 1 and 2, the plate 1 being movable relative to the plate 2, reference being had to Fig. 1. The base-plates 1 and 2 are adapted to be aligned with their

lateral edges abutting each other, forming a continuous base upon which the plaster-cast model is to be mounted.

The movement of the base-plate 1 relative to the base-plate 2 is accomplished through actuation of the micrometer screw 3, referring to Fig. 2. This screw 3 is also the medium joining the base-plates 1 and 2 in movable relationship, being disposed in the aligning openings extending, laterally and centrally, therethrough the base-plates. In the base-plate 1 the opening is in form of a partly tapped hole, the threaded portion of the screw 3 engaging with the threaded portion of the opening. In the base-plate 2 the opening assumes the form of a through hole acting as a bearing for the shank of the screw 3. The protruding extremity of the screw 3 is here shown provided with a knurled head to facilitate manipulating. Thus by turning the screw 3 in the proper direction, the base-plate 1 will be moved away from or towards the base-plate 2, the movement of the base-plate 1 taking place in a horizontal plane, coincident with the plane of the base-plate 2, and parallel thereto.

That the base-plates 1 and 2 may be held in alignment during the entire range of movement of the plate 1, the plate 2 is provided with the guide pins 4 permanently set therein, and the plate 1 is provided with the co-operating bearing holes 5 therefor, referring to Fig. 4. There has been arbitrarily indicated two guide pins 4, one on each side of the screw 3.

The measure of movement of the base-plate 1 relative to the base-plate 2 is visibly indicated on the scale, shown divided into millimeters, reference being had to Fig. 1, provided for this purpose along the front edge of the base-plate 1. The indicating pointer 6 is fixedly positioned along the front edge of the base-plate 2, to register with scale on the plate 1, giving direct readings of the value of the movement of the base-plate 1.

There has been shown, referring to Fig. 1, the walls 7 raised along three edges of each of the base-plates 1 and 2. The provision of these walls 7 facilitate mounting of the plaster-cast or stone models upon the base-plates, and by confining the size and shape of the models to occupy the space between the said walls, the ease of handling and storing the models is promoted. To hold the model in its position on the base-plates 1 and

2, there has been provided the retaining screws 8, of length sufficient to extend into the body of the model. These screws 8 are disposed in tapped holes, placed centrally, 5 at internally bossed areas along the front and rear walls of each of the base-plates.

The technique procedure for use of the device is as follows: The micrometer screw 3 is regulated so that the adjacent edges of 10 the base-plates 1 and 2 are flush with each other, the pointer 6 indicating "0" on the scale, and the retaining screws 8 are set so that the threaded portion of each screw extends as far as possible within the walled 15 space of the base-plates. The impression of the tooth bite having been taken, the process of pouring the model, a plaster-cast model being here assumed for illustration, is carried out in the usual manner, the model being 20 poured directly upon the base-plates of the device. Before pouring the model the attaching lug receptacles 12, for seating the orthodontic appliance, should be incorporated with the impression, so that they become 25 firmly positioned on the model when hardened. When the plaster has been allowed to harden, the surplus is trimmed from the model, the retaining screws 8 withdrawn from the body of the model, and the model 30 removed from the device. The model is then sawed into two sections 9 and 10, reference being had to Fig. 1, the cut being made along the reference line formed on the lower surface of the model by the junction of the adjacent edges of the base-plates. The two 35 sections 9 and 10 of the model are now replaced in their respective positions on the base-plates, and the retaining screws are set to securely clamp the models in place.

40 The orthodontic correcting appliance which it is assumed is to be regulated, is then disposed in position on the model with its anchoring or attaching lugs registering within their respective receptacles 12. The 45 regulation of the appliance 11 is preformed by manipulation of the micrometer screw 3, the degree of distention desired being controlled by the movement of the screw 3. When the appliance 11 has been distended to 50 possess the required tensional adjustment necessary to be exerted against the malposed tooth or teeth in the mouth, and while the appliance is in position on the model, a heating means such as a torch flame or electric current is applied thereto until the metal has 55 become annealed. Upon subsequent hardening of the metal, the appliance will have assumed a permanent set of its newly adjusted form. The appliance is then ready to 60 be removed from the model and fitted in the mouth.

As it is generally necessary to regulate the adjustment of the correcting appliance more than once, before the malposed tooth or teeth 65 have been shifted to their normal or approxi-

mately normal position in the dental arch, and as this is accomplished in progressive steps extending over a period of time, it will be necessary to preform corresponding regulations of the appliance to produce these 70 further adjustiments. Succeeding regulations in the adjustment of the correcting appliance are carried out by the repetition of the process outlined hereinbefore.

The device embodied in my invention can 75 be employed for distending, contracting or crimping practically any type of orthodontic correcting appliance, whether of the arch-bow type or otherwise, and functioning either internally or externally of the dental 80 arch.

While I have described and illustrated in the foregoing a preferred embodiment of my invention, it is to be understood that I do not limit myself to the details of construction and arrangement of the parts hereinbefore set forth and shown, but reserve the privilege to resort to such modifications and changes within the spirit and scope of 90 the appending claims.

What I claim is:

1. A device for regulating the adjustment of orthodontic correcting appliances, comprising separate mounting members adapted to removably support a dental model split into sections and a correcting appliance removably supported on said model, and an actuating means for the mounting members for moving one section of the model relative to another section thereof to cause a change 100 in the form of the correcting appliance.

2. A device for regulating the adjustment of orthodontic correcting appliances, comprising a pair of separate base-plate members adapted to removably support substantially half sections of a dental model and a correcting appliance removably supported upon said model the model being provided with a means for attaching the appliance upon the model, means for rigidly supporting the sections of said model upon the base-plate members, and a micrometer actuating screw member for moving one section of 110 said model relative to the other section.

3. A device for regulating the adjustment of orthodontic correcting appliances, comprising a pair of separate base-plate members adapted to removably support substantially half sections of a dental model and a correcting appliance removably supported upon said model the model being provided with a means for attaching the appliance upon the model, a retaining screw means for rigidly supporting the sections of said model 120 upon their respective base-plate members, a micrometer actuating screw member disposed to operate in horizontally positioned co-operating openings through the said base-plate members for moving one section of 125 said model relative to the other section in the 130

same horizontal plane, and a means for measuring the distance one section of said model is moved relative to the other section.

4. A device for regulating the adjustment of orthodontic correcting appliances, comprising a base-plate member adapted to removably support one section of a dental model and a second base-plate member adapted to removably support the other section of said model in movable relationship to the first section and a correcting appliance removably supported upon both sections of said model co-operatively positioned the model being provided with an attaching lug receptacle means for detachably supporting the appliance upon the model, a screw member for rigidly retaining each section of said model upon its respective base-plate member, a micrometer actuating screw member for moving one section of said model relative to the other section distally and parallel to each other and in the same horizontal plane, and an indicator measuring means of the distance between the two sections of said model for any adjustment of the said appliance.

5. A device for regulating the adjustment of orthodontic correcting appliances, comprising a pair of separate base-plate members adapted to removably support a dental

model split vertically and longitudinally in substantially half sections and a correcting appliance removably supported upon said model the model being provided with an attaching lug receptacle elements permanently positioned upon said model for the said appliance, guide pin members for aligning the said two base-plate members fixedly positioned in one of the base-plate members, cooperating receptacle means for the said guide pin members provided in the other base-plate member, a retaining means for rigidly clamping each section of said model upon its respective base-plate member, a micrometer actuating screw member disposed with the shank thereof in a through hole horizontally positioned in one of the base-plate members and with the threaded portion thereof engaging within a correspondingly threaded hole horizontally positioned in the other base-plate member, and a measuring means for indicating the distance one base-plate is caused to move relative to the other.

Signed at Pelham Manor, in the county of Westchester and State of New York, this 14th day of June A. D. 1925.

PERCY NORMAN WILLIAMS.
